EMBALMING APPARATUS

Harry S. Day, North Benton, Ohio

Application April 28, 1942, Serial No. 440,766

4 Claims. (Cl. 27—24)

This invention relates to an embalming apparatus and more particularly to a drainage tube adapted to be inserted into the deeper blood carrying vessels of a body to facilitate the drainage of the blood and other fluids therefrom.

The principal object of the invention is the provision of a drainage tube capable of providing a positive drainage channel when used in connection with, by the insertion thereinto, of the deeper blood carrying vessels of a body.

A further object of the invention is the provision of a drainage tube adapted to be inserted into the deeper blood carrying vessels of a human body and provided with mechanical means for causing a removal of clots or other blood blocking formations which are commonly found in and about the heart areas.

A still further object of the invention is the provision of a drainage tube capable of being inserted into the deeper blood carrying vessels of the human body and so formed that fluids may be introduced through a portion thereof and utilized in creating a jet pump action to facilitate the removal of blood blocking formations in the blood carrying vessels.

The drainage tube shown and described herein has been designed for use in embalming practices both according to heretofore conventional forms of embalming whereby pumping actions are employed and more particularly in connection with the method of embalming set forth in my Patent #2,286,173 of December 16, 1941 wherein, generally speaking, an artificial respiration of the body tissues including the veins and the arteries is accomplished by subjecting the body to alternate pressures and vacuums, the drainage tube forming the subject of this invention becomes an essential portion of the apparatus necessary to prevent the deeper vessels of the body from collapsing while practicing this new method of embalming.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed without departing from the spirit of the invention.

The invention is illustrated in the accompanying drawing, wherein:

Figure 1 is a side elevation with parts broken away and parts in cross-section illustrating the drainage tube, with considerable enlargement.

Figure 2 is a top plan view taken on lines 2—2 of Figure 1.

By referring to the drawing and Figure 1 in particular, it will be seen that the subject of this invention comprises a drainage tube generally indicated by the numeral 10 the lowermost portion 11 of which is preferably formed at an angle to the remainder so as to facilitate the placement of the drainage tube into any one of the several deeper blood carrying vessels of the human body, when the same are opened slightly above the bifurcation of the right and left common iliac arteries or veins. A central section of the drainage tube is preferably formed in a flexible manner and generally indicated by the numeral 12, in actual practice may be formed of rubber or other resilient material reinforced non-collapsible reinforcement comprising a metallic coil as is commonly known and employed in the art for this purpose. The uppermost portion of the drainage tube 10 is shown in Figure 1 in cross-sectional detail and it will be observed that a web member 13 is positioned across the opening at the end of the tube 10 and that the web member 13 is preferably arched so that a boss 14 positioned centrally thereof lies above the plane of the end of the tube 10. Inwardly from the uppermost end of the tube there is positioned a secondary web 15 which is preferably provided with a centrally positioned boss 16 and functioning on bearings set in the bosses 14 and 16 there is a revolvable cage-like structure preferably of wire formation and generally indicated in the drawing by the numeral 17. It will be seen that the uppermost or outermost portion of the cage-like revolvable member 17 is arched to conform more or less with the shape of the web member 13 and so as to extend partly beyond the end of the tube 10. It will also be seen that depending beneath the boss 16 of the secondary web 15 there is a spiral vane 18 which is adapted to be rotated by the direction thereagainst of the stream of fluid or air such as may be conveyed and directed through a jet 19 forming the delivery orifice of a secondary tube 20 which as is illustrated in Figure 1 is positioned externally of the drainage tube 10 throughout most of its length and communicates with the interior of the drainage tube 10 at a point slightly above the position of the spiral vane 18 so that the jet 19 is directed downwardly or inwardly of the tube 10 and which will, for example, at such time as fluid is being emitted therefrom have the dual purpose of both rotating the spiral vane 18 and the cage-like revolvable member 17 attached thereto and simultaneously

causing a jet pump action within the drainage tube 10 which action is due primarily to a restriction 21 adjacent the discharge orifice of the jet 19 the restriction being formed within the tube 10.

As will thus be seen a drainage tube formed in accordance with this invention may be inserted into said blood carrying vessels in a human body preferably through openings formed in the sacroiliac area and which drainage tube would, for example, be inserted upwardly into the abdominal aorta and/or into the inferior vena cava, it being observed that a tube when being inserted into the abdominal aorta would necessarily be of a length approximately 18 inches, so as to insure its reaching the aortic arch immediately above and toward one side of the heart and in which area blood clots and other blood blocking formations are commonly located. It will be seen that in accordance with this invention, clots or other blood blocking formations in any of the deeper blood vessels of the body or in the aortic arch area of the heart can be readily and speedily removed due to the suction action of the jet pump formed by the jet 19 and the restriction 21 of the drainage tube and to the mechanical action which will tend to break up clots and other blood blocking formations, that of the revolving cage-like member 17. Thus it will be observed that clots and other blood blocking formations heretofore often incapable of being removed may be readily and speedily removed with the drainage tube, the subject of this invention, and the complete embalming of the body thereby insured due to the definite removal of objects otherwise blocking the arteries and veins and particularly the abdominal aorta, the aortic arch thereof, the inferior vena cava, and the right and left common iliac arteries and veins thus enabling these vessels to be used for the generally known and practiced introduction of capillary washing fluids to insure the removal of blood particles and the subsequent introduction of embalming fluids into the body therethrough.

In a drainage tube formed in accordance with this invention having an overall length of approximately 18 inches the outer diameter would preferably be $\frac{5}{8}$ of an inch and due to the known expanding properties of the various deeper vessels of the human body, the secondary tube 20 is easily accommodated when positioned along the outermost surface of the drainage tube 10 particularly when it is flattened in accordance with this invention. It will be obvious to those skilled in the art that modifications of this invention are possible particularly as to shape and length, for example, tubes of smaller diameter and of longer length and having more than one flexible section might quite obviously be used in penetrating the common iliac arteries and veins reaching into the femoral arteries and veins for the removal of clots or other blood blocking formations. Tubes formed according to the invention except as for modifications as to size and shape might also be employed in establishing communication channels for the positive removal of clots and other blood blocking forma-

tions in other deeper vessels of the human body not hereinbefore mentioned.

By referring to Figure 2 of the drawing, the relative size and positioning of the cage-like revolvable member 17 may be seen and in addition thereto the relative size and positioning of the secondary tube 20 and the jet 19 forming the delivery orifice thereof as well as the restriction 21. It being obvious in connection therewith that the restriction may be varied in accordance with the known principles of jet propelling of fluids.

Having thus described my invention, what I claim is:

15. 1. A noncollapsible tubular member open at both ends and provided with a flexible midsection, a secondary tubular member attached to the said tubular member one end of which secondary tubular member terminates inwardly from one end of the said tubular member and faces inwardly from the said end of the tubular member so that liquid introduced through the secondary member effects a jet pump action in connection with the said tubular member to assist in removing the clots and blood blocking formations from the vessels of a human body into which the said tubular members are adapted to be inserted.
20. 2. A noncollapsible tubular member open at both ends and provided with a flexible section, a restriction formed in said tubular member inwardly from one end thereof, a secondary tubular member attached to the said tubular member one end of which secondary tubular member terminates inwardly from one end of the said tubular member and faces inwardly therefrom so that liquid introduced therethrough effects a jet pump action in connection with the said restriction in the said tubular member to assist in removing clots and blood blocking formations from the vessels of a human body into which the said tubular members are adapted to be inserted.
25. 3. A drainage tube comprising a section of tubular material having a flexible portion, a rotatable cage-like member positioned within one end of the said drainage tube, means for rotating the said cage-like member said means comprising a liquid delivery jet.
30. 4. A drainage tube adapted to be inserted into one of the deeper vessels of a human body said drainage tube being formed of noncollapsible material and having a flexible section, restriction formed inwardly from one end thereof, a rotatable cage-like member positioned in one end of the said drainage tube adjacent the said restriction, a secondary tubular member one end of which terminates adjacent the said restriction and which secondary tubular member is adapted to deliver fluid inwardly from the end of the drainage tube in which the revolvable cage-like member is positioned, vane means formed on the said cage-like member and adjacent the delivery orifice of the said secondary tubular member so that liquid delivered therethrough will cause the said cage-like member to rotate.
35. 5. A drainage tube comprising a section of tubular material having a flexible portion, a rotatable cage-like member positioned within one end of the said drainage tube, means for rotating the said cage-like member said means comprising a liquid delivery jet.
40. 6. A drainage tube adapted to be inserted into one of the deeper vessels of a human body said drainage tube being formed of noncollapsible material and having a flexible section, restriction formed inwardly from one end thereof, a rotatable cage-like member positioned in one end of the said drainage tube adjacent the said restriction, a secondary tubular member one end of which terminates adjacent the said restriction and which secondary tubular member is adapted to deliver fluid inwardly from the end of the drainage tube in which the revolvable cage-like member is positioned, vane means formed on the said cage-like member and adjacent the delivery orifice of the said secondary tubular member so that liquid delivered therethrough will cause the said cage-like member to rotate.
45. 7. A drainage tube comprising a section of tubular material having a flexible portion, a rotatable cage-like member positioned within one end of the said drainage tube, means for rotating the said cage-like member said means comprising a liquid delivery jet.
50. 8. A drainage tube adapted to be inserted into one of the deeper vessels of a human body said drainage tube being formed of noncollapsible material and having a flexible section, restriction formed inwardly from one end thereof, a rotatable cage-like member positioned in one end of the said drainage tube adjacent the said restriction, a secondary tubular member one end of which terminates adjacent the said restriction and which secondary tubular member is adapted to deliver fluid inwardly from the end of the drainage tube in which the revolvable cage-like member is positioned, vane means formed on the said cage-like member and adjacent the delivery orifice of the said secondary tubular member so that liquid delivered therethrough will cause the said cage-like member to rotate.
55. 9. A drainage tube comprising a section of tubular material having a flexible portion, a rotatable cage-like member positioned within one end of the said drainage tube, means for rotating the said cage-like member said means comprising a liquid delivery jet.
60. 10. A drainage tube adapted to be inserted into one of the deeper vessels of a human body said drainage tube being formed of noncollapsible material and having a flexible section, restriction formed inwardly from one end thereof, a rotatable cage-like member positioned in one end of the said drainage tube adjacent the said restriction, a secondary tubular member one end of which terminates adjacent the said restriction and which secondary tubular member is adapted to deliver fluid inwardly from the end of the drainage tube in which the revolvable cage-like member is positioned, vane means formed on the said cage-like member and adjacent the delivery orifice of the said secondary tubular member so that liquid delivered therethrough will cause the said cage-like member to rotate.
65. 11. A drainage tube comprising a section of tubular material having a flexible portion, a rotatable cage-like member positioned within one end of the said drainage tube, means for rotating the said cage-like member said means comprising a liquid delivery jet.
